UNITED STATES PATENT OFFICE.

ELISHA SEYMOUR, OF CHICAGO, ILLINOIS.

ROTATING CUT-OFF VALVE.

SPECIFICATION forming part of Letters Patent No. 607,089, dated July 12, 1898.

Application filed August 21, 1897. Serial No. 649,021. (No model.)

To all whom it may concern:

Be it known that I, ELISHA SEYMOUR, a citizen of the United States, residing in Chicago, in the county of Cook and State of Illinois, have invented a new and useful Improvement 5 in Rotating Cut-Off Valves, of which the following is a specification.

My invention relates to rotating cut-off valves for steam-engines.

10 The object of my invention is to provide a rotating cut-off valve of a simple, efficient, and durable construction, by means of which the time of cut off of steam to the engine-cylinder may be regulated according to the 15 load upon the engine from time to time.

With this object in view my invention consists in the combination of a rotating valve and a rotatable expansion-ring provided with a pair of segmental slots, openings, or ports 20 for the passage of the steam in connection with a pair of stops fitting into said segmental slots or ports, so that by the rotation or adjustment of the expansion-ring the operative length or extent of the segmental slots 25 or ports may be regulated from time to time, as required, and thus govern the time and quantity of steam admitted to the cylinder, while the port of the rotating valve is over and passing the segmental slot in the expansion-ring. 30

My invention also consists in the novel devices and in the novel combinations of parts and devices herein shown and described, and specified in the claims.

35 In the accompanying drawings, forming a part of this specification, and in which similar letters of reference indicate like parts throughout the several views, Figure 1 is a central sectional view of a rotating cut-off valve embodying my invention. Fig. 2 is a 40 plan view with the top plate of the valve-case removed. Fig. 3 is a horizontal section on the line 3 3 of Fig. 1. Fig. 4 is a horizontal section on the line 4 4 of Fig. 1, and Fig. 45 5 is a detail section taken on the line 5 5 of Fig. 4.

In the drawings I have for convenience illustrated my invention in the form designed for use on a reciprocating engine. It is, however, 50 equally adapted for use upon rotary engines by simply suitably changing the location and number of the ports.

In the drawings, A represents a portion of an engine-cylinder of any suitable construction known to those skilled in the art. 55

B is the valve-case, the same comprising a top plate B', a cylindrical portion B², and a bottom plate B³, the latter being secured to the engine-cylinder.

D is the rotating valve, secured to a suitable shaft D', journaled in the valve-case B and packed thereto by a stuffing-box or packing-ring D². The rotating valve D is provided with a port d, through which steam entering from the port b in the valve-casing may 60 pass to the engine-cylinder as the valve D rotates. The valve D is further provided with a segmental slot or cut-out portion d' on its periphery at its under side, which serves as an exhaust-port through which the steam may 65 escape from the valve-casing through the exhaust-port b². 70

Beneath the rotating valve D is a rotatable or adjustable expansion-ring F, provided with a pair of segmental slots or ports f f, each 75 preferably in length about one-fourth the circumference, through one of which the live steam passes on its way to the engine-cylinder while the exhaust escapes through the other. The base-plate B³ of the valve-casing is provided with a pair of stops b³, projecting from the upper face of the base-plate into and fitting the segmental slots or ports f f in the expansion-ring F, so that by turning the expansion-ring on its axis these stops will serve 80 to vary or regulate the operative length of the segmental slots or ports f f, and thus vary the quantity of steam admitted to the cylinder at each stroke and also the time of its admission, as the shorter the segmental slot or 85 port f in the expansion-ring the quicker will the port b in the rotating cut-off valve D be in passing. By turning the rotatable expansion-ring F in the direction to lengthen the operative length of the slots or ports f in 90 the expansion-ring F the longer will the port d in the valve D be in passing the segmental slot or port f and the greater will be the quantity of steam admitted to the cylinder and the less will be the number of expansions 95 of the steam in the engine-cylinder. When the load upon the engine is light, by simply turning the expansion-ring in the direction to shorten the operative length of the ports 100

or slots f the quicker will the port d be in passing and the greater will be the relative proportion of time during each rotation of the valve D when the live steam is cut off from 5 the engine-cylinder and the greater will consequently be the number of expansions.

The rotating valve D or its shaft D' may be continuously rotated by any suitable mechanism. As illustrated in the drawings, I have 10 provided the valve-shaft D' with a gear D⁴, which is a convenient means for giving a positive rotary motion to the valve.

The rotatable or adjustable expansion-ring F may be rotated or adjusted from time to 15 time, as required, by any suitable mechanism. As illustrated in the drawings, I have shown, as a convenient means for rotating or oscillating the expansion-ring in either direction, as required, a segment-gear f' , which meshes 20 with a gear f^2 on a shaft f^3 , which may be provided with a lever or other mechanism for turning it by hand or by connection with the governor of the engine.

I claim—

25 1. A rotating cut-off valve for steam-engines, comprising in combination a valve-casing having a base or bottom plate, a rotating valve in said case provided with ports, an expansion-ring beneath said valve provided 30 with segmental slots or ports, said base or

bottom plate of the casing having stops projecting into and fitting said segmental slots or ports in said expansion-ring so that the operative length of said segmental slots or ports may be adjusted or regulated as required by turning or oscillating the expansion-ring, and the time and the amount of steam admitted and number of expansions governed from time to time as may be required, substantially as specified. 35

2. In a rotating cut-off valve, the combination with a casing having bottom plate B³ provided with stops b^3 b^3 , an oscillating expansion-ring F provided with segmental slots or ports f f , and a rotating valve D provided with ports d d' , mechanism for rotating said valve D, and means for turning or oscillating said expansion-ring, substantially as specified. 40

3. The combination with a valve-case, of a 45 rotating valve D therein, an expansion-ring F provided with segmental slots or ports f f , and stationary stops b^3 b^3 fitting in said segmental slots or ports f f , substantially as specified.

ELISHA SEYMOUR.
